UNITED STATES PATENT OFFICE.

YVES D'AVY, OF OPELOUSAS, LOUISIANA.

BRICK-MACHINE.

1,394,285.

Specification of Letters Patent.

Patented Oct. 18, 1921.

Application filed May 27, 1920. Serial No. 384,576.

To all whom it may concern:

Be it known that YVES D'AVY, a citizen of the United States of America, residing at Opelousas, in the parish of St. Landry 5 and State of Louisiana, has invented new and useful Improvements in Brick-Machines, of which the following is a specification.

The object of the invention is to provide 10 a simple and efficient device adapted for use in forming bricks or building blocks by hand as distinguished from the machines which are used for forming the same in larger quantities, and more especially the 15 object in view is to provide a device adapted for hand manipulation by which uniformity of the product may be secured with the minimum effort upon the part of the operator and with these objects in view the invention 20 consists in a construction and combination of parts of which a preferred embodiment is shown in the accompanying drawings, wherein:—

Figure 1 is a side view of the same with 25 the parts arranged in the position which they assume just prior to the advancement of the follower for expelling the molded brick blanks from the form.

Fig. 2 is a detail view in perspective of 30 the follower.

Fig. 3 is a similar view of the form.

Fig. 4 is a transverse sectional view of the parts in the position in which they are illustrated in Fig. 1.

35 The device consists essentially of the form member 10 which may be provided with any suitable or desired number of compartments 11 which are open top and bottom for the reception of the clay or other plastic material of which the product or bricks are to 40 be formed and a follower member 12 which is of a construction complementary of the forming member and is adapted to be moved relatively to the latter after material has 45 been molded in the compartments of the form to expel the blanks from the compartments under such conditions as to leave them exposed at their surfaces for drying and subsequent baking.

50 In the construction illustrated the form consists of the side walls 13 connected by transverse webs 14 to form compartments 11 of the dimensions desired for the bricks or building blocks, said walls being extended beyond the terminal webs to form

ears 15 connected transversely by rounds 16 constituting handles or clips.

The follower consists of a plate 17 to which are attached terminal ears 18 adapted for sliding engagement with the exterior 60 surfaces of the terminal webs 14 of the form member as indicated in Fig. 1, and plungers 19 corresponding in number and dimensions with the compartments 11 of the form member and consisting of folded plates secured 65 to the body plate 17 and spaced apart at their adjacent edges to form intervals 20 of a width sufficient to receive the intermediate webs 14 to the end that when the follower member is disposed in relation to the 70 form member as indicated in Fig. 1 and is held in a fixed position with the plungers 19 upon the surfaces of the clay contents of the chambers 11 and the form member is raised relatively to the follower until the 75 upper edges of the walls 13 and webs 14 are in contact with the under surface of the plate 17 the blanks which have been molded in the chambers of the form member will be left in proper position and in spaced relation upon a pallet or other surface indicated at 21 to permit of their direction and transportation to the oven for baking. The plungers are preferably of a depth to project 80 from a plain of the plate 17 which corresponds with the depth of the chamber or compartment 11 of the form member as will be obvious by reference to Fig. 4 and the extremities of the carrying plate 17 preferably project beyond the plains of the guide 85 ears 18 to a distance sufficient to form clips which may be engaged by the hands of the operator as the handles or clips 16 are engaged, to cause the relative movement of the members necessary to expel the molded clay 90 from the compartments or chambers of the form member.

What is claimed is:

1. A brick making device comprising complementary form and follower members, the 100 form member being provided with a series of molding chambers and consisting of parallel side walls and transversely spanning terminal and intermediate webs connecting the side walls, transverse clip rounds connecting the extremities of the side walls beyond the terminal webs, the follower member having depending guide ears adapted for sliding engagement with the exterior surface of the terminal webs of the form members, 110

and a series of intermediate plungers terminally spaced apart and from said guide ears to form intervals for the reception respectively of said terminal and intermediate webs, the said guide ears being of a height equal to twice the height of the form member to dispose the plungers in spaced relation to a pallet for the purpose specified.

2. A hand brick forming device consisting of complementary form and follower members of which the form member is of compartmental construction and open at its top and bottom, the follower members hav-

ing a series of plungers disposed for insertion in the compartments of the form member and dimensioned with respect thereto, the follower member being provided with depending terminal ears of a length sufficient to dispose the plunger members a distance above the pallet equal to the height of the form member for the purpose specified.

In testimony whereof he affixes his signature.

YVES D'AVY.
